UNITED STATES PATENT OFFICE.

ARLO E. RICE, OF OLIVET, SOUTH DAKOTA.

DESIGN FOR A COMBINATION-TOOL.

18,231.

Specification for Design.

Patented Nov. 30, 1915.

Application filed September 13, 1915. Serial No. 50,521. Term of patent 14 years.

To all whom it may concern:

Be it known that I, ARLO E. RICE, a citizen of the United States, residing at Olivet, in the county of Hutchinson and State of South Dakota, have invented a new, original, and ornamental Design for a Combination-Tool, of which the following is a specification, reference being had to the accompanying drawing, forming part thereof.

The figure is a face view of a combination tool embodying my design.

I claim:

The ornamental design for a combination tool, as shown.

ARLO E. RICE.

Witnesses:

GOTTLOB HAAR,
GUSTAVE DEWALD.
